UNITED STATES PATENT OFFICE

2,067,160

AIR CLEANER AND SILENCER

George C. Kensink, Denver, Colo.

Application July 22, 1935, Serial No. 32,549

7 Claims. (Cl. 183—72)

My invention relates to an air cleaner and silencer, and is an improvement over a similar device which is set forth in a United States Patent No. 1,994,006 granted to me on March 12, 1935.

5 The main object of the invention is to provide an air cleaner and silencer for all uses where such a device may be employed, but particularly for internal combustion engines; the dust, before coming in contact with the cleaner being raised 10 against gravity whereby the heavy particles in the dust are eliminated.

A further object of the invention is to provide a screen which automatically and continuously 15 cleans or rids itself of all dust particles and therefore cannot become clogged, which does not restrict the flow of air therethrough, and which is not affected by climatic conditions.

20 A further object is to provide an air cleaner and silencer which is adaptable for either up or down draft carburetors, and in which the silencer element is in the form of a reversible unit which may be removed when not required, the cleaner requiring no attention throughout its life, the units comprising the device being so connected 25 that they may be quickly assembled or removed, and the construction being such that the air is always drawn in through the bottom of the device.

These and other objects are accomplished in 30 the manner set forth in the accompanying drawings in which:

Figure 1 is a view partly in section and partly in side elevation, showing the device as arranged for attachment to a down draft carburetor;

35 Figure 2 is a view similar to Figure 1, but showing the parts as arranged, when the device is used for an up draft carburetor;

Figure 3 is a view partly in side elevation and partly in section, the sound silencing element having 40 been removed, and different means being shown for holding the bottom plate in clamped relation to the air cleaner, the arrangement being for an up draft carburetor;

Figure 4 is a view similar to Figure 1, but showing 45 a different style of air cleaning element;

Figure 5 is a view similar to Figure 4, the sound silencing element being removed, the bottom plate being clamped against the air cleaner by a reversed arrangement of the clamping means shown 50 in Figure 3, this arrangement being for a down draft carburetor;

Figure 6 is a vertical section through a portion of the silencer assembly and is taken on line 6—6, Figure 7;

55 Figure 7 is a section taken on line 7—7, Figure 6;

Figure 8 is a fragmentary section showing one way of holding one of the diaphragms in place;

60 Figure 9 is a fragmentary section showing one type of joint between the tube and cleaner plate;

Figure 10 is a bottom plan view of a portion of the device, looking in the direction of arrow 10 in Figure 3;

Figure 11 is a section through the cleaner element showing a crimped joint between the ends 5 thereof;

Figure 12 is a vertical section through the filter element showing the construction thereof to a somewhat enlarged scale; and

Figure 13 is a section through one side of the 10 silencer assembly, similar to the sections shown in Figures 4 and 5 and shows a slightly modified construction.

In the drawings letter A designates the cylindrical casing or housing in which the filter and the 15 silencing elements are located. The casing, as shown, is formed from a cylindrical wall 1 and an upwardly bulging top 2 having its outer edge 3 downwardly flared and connected with the upper edge of the cylindrical wall by a crimped 20 joint 4, or by any other type of joint.

When material having the proper ductility is used the wall and the top can be drawn or spun from a single piece. The top is provided with an aperture 5 and the surface surrounding this aperture is upwardly flared as indicated at 6. The lower edge of the cylindrical wall is bent inwardly and upwardly, so as to lie along the inside of the wall as indicated by reference numeral 7 and the upper edge of this fold is turned inwardly so as 30 to provide a flange 8.

An annular bottom plate 9 has its outer edge resting against the under surface of flange 8 and has an annular downwardly convex portion 10 whose center is cut away to form an aperture 11. 35 The bottom, directly surrounding the opening 11, is flared or inclined in the same manner and preferably to the same extent as the portion of the top indicated by numeral 6.

The bottom is provided (in Figures 1, 2 and 3) 40 with two concentric circular beads 12 whose concave surfaces are on the top and serve as supports for the filter elements 13 and 14, whose upper ends engage the concave under-surface of the positioning ring 15 that is attached to the underside of 45 the top by means of brackets 16, to which the ring is connected by bolts 17. The filter elements 13 and 14, as shown in Figures 1, 2 and 3, are frusto-conical, the inner one tapering downwardly and the outer one, tapering upwardly and when 50 in position have their lower edges positioned in the spaced depressions of beads 12 and their upper edges positioned in the concave portion of ring 15. Referring now to Figure 10, it will be seen that the bottom 9 is provided with a plurality of 55 arcuate openings 18 that are positioned between the beads 12 and serve to admit air into the space between the filter elements.

Referring now, more particularly to Figure 3, it will be seen that the bottom is attached to the 60

brackets 16 by bolts 19 which project through openings 20 in the bottom and through openings in the brackets; these bolts pass through the space between the filter elements and are provided with nuts 21 that serve to clamp the filter elements and hold them in position.

The brackets are removably secured to the top by bolts 22. The arrangement illustrated in Figure 3 is for an up draft carburetor and a tubular connector 23, which is provided with a frustoconical flange 24, is positioned on the cover and rests on the flared surface 6. A ring 25 projects over the flange 24 and is secured to the top by means of bolts 26 that also secure the ends of a V-shaped supporting strap whose arms have been designated by numeral 27. A bolt 28 passes through an opening in the bottom of the supporting strap and through an opening in the disk 29 which closes the aperture 11.

The disk 29 has a flaring edge that fits against the corresponding flared surface of the bottom directly surrounding the aperture 11. When nut 30 is tightened, disk 29 will be firmly secured in position.

The tubular member 23 is provided with a plurality of slits 31 and is surrounded by a strap 32 whose ends 33 extend radially and are provided with openings 34 for the reception of a clamping bolt, which has not been shown.

If the cleaner is to be used with a down draft carburetor the tubular member 23 is placed at the bottom and in communication with aperture 11. The clamping ring 25 is also transferred to the bottom and is held in position by the bolts 26 which now pass through openings 35 that are provided for this purpose, and which are closed by suitable means when not in use. The disk 29 is now used to close the aperture 5, all as shown in Figure 5.

Let us now assume that the cleaner illustrated in Figure 3 is attached to a carburetor and that the engine is operating. The air for the engine will enter the space between the filter elements through openings 18 (see Figure 10) in the bottom 9, and will pass through the filter elements into the interior of the cleaner and thence to the carburetor and the engine. By the arrangement of filter elements shown in Figures 1, 2 and 3, their areas are increased twofold over that shown in Figures 4 and 5.

The filter elements are formed from a special air filter fabric which is made from matted fibers and which has been designated by reference numeral 36 in Figures 11 and 12. On the inside surface of the filter material a fine wire screen 37 is positioned and on opposite sides of the assembly woven wire screen members 38 are located. The ends are connected by a crimped joint 39. By using a fine screen 37 on the suction side of the filter layer 36, the latter can be thinner than otherwise practical, as the fine mesh screen will reinforce it and prevent it from being pulled through the openings in the screen 38.

The filter material 36 is compacted between the woven wire screens which hold the fibers in place with the result that the outer surface soon becomes quite smooth and compact since the wires of the outside screen sink into the filter material and the fibers are forced inwardly by the entering air so that dust particles will not accumulate on the filter surface.

The filter, being mounted on an engine or on an automobile or tractor is subjected to constant vibration, which, it has been found, loosens any

dust and dirt with the result that the cleaner does not require any servicing.

From the above description and from an inspection of Figures 1 and 2, it will be apparent that the casing is always positioned with its open end downwardly, and since the cleaner is of ample size (approximately ten inches in diameter) the velocity of the air as it enters from below is very low with the result that only a small proportion of the dust carried by the air enters, as the velocity is not sufficient to raise it against the action of gravity, and this also prevents the entry of moisture particles.

It is often desirable to eliminate the noise due to the intake of the air at the carburetor and when this is to be done the cleaners illustrated in Figures 3 and 5 are modified by the addition of silencing material.

Referring now to Figures 1 and 2, it will be seen that the supporting strap 27 has been removed and that a silencing assembly has been substituted therefor which consists of a cylindrical member 40 of foraminated sheet metal. Connected to the lower edge of member 40, by a crimped joint 41 is an annular plate 42 which is curved transversely so as to fit the inside of the corresponding portion 10 of the bottom.

Connected with the inner edge of plate 42, by a crimped joint 43, is a cylindrical member 44. An annular diaphragm 45, shaped as shown in Figures 1 and 2, is attached to the upper edge (Figure 1) of the cylindrical member 44 by a crimped joint 46 and the outer edge of this diaphragm is curved downwardly and terminates in a circular flange 47 that engages the inner surface of member 40 directly beneath the inwardly projecting bead 48. The parts 42, 44 and 45 cooperate with a portion of the inner surface of member 40 to form an annular chamber 49 that is filled with cotton. A layer of cheese cloth is positioned between the cotton and the walls to prevent fibers from being sucked through the openings. Instead of cotton any other similar fibrous material can be used.

Member 40 has a second bead 51 that is located above bead 48 (Figure 1) and a circular diaphragm 52 has its outer edge curved upwardly as indicated by numeral 53, and in engagement with the inside of member 40 above bead 51. The diaphragm 52 is concave on its lower side, as shown in the drawings.

The compartment formed by the diaphragm 52 and upper portion of the cylindrical member 40 is filled with silencing material, such as cotton, and this compartment is then closed by a cover whose outer edge is connected to the upper edge by a crimped joint 55.

Bolts 56 extend through openings in member 42 and are so positioned that they enter the holes 35 (Figure 3). A bolt 57 projects through a central opening in the cover plate 54 and through the opening in the disk 29. Bolts 56 and 57 cooperate with the silencer assembly to hold the bottom 9 in place and this takes the place of the V-shaped strap 27 and bolts 26 and 28 shown in Figure 3.

The silencer assembly just described is reversible, as shown in Figures 1 and 2, to make the cleaner and silencer suitable for either a down draft carburetor (Figure 1) or an up draft carburetor (Figure 2). In Figures 1 and 2, the clamping ring 25 has been omitted and flange 24 located on the inside and held in position by member 42.

Applicant does not want to be limited to either of these constructions. The large openings 58 in member 40 are provided for convenience only as the member 40 is foraminated and sufficient air can enter through the foraminations.

Since Figure 2 is a reversal of the arrangement shown in Figure 1, and since the parts have been given the same reference numerals in both figures, no description of Figure 2 will be given.

10 When the words "above" or "below" are used, reference is had to Figure 1.

The structures illustrated in Figures 4 and 5 differ from the structures shown respectively in Figures 1 and 3 principally in this, that in the latter two filter elements 13 and 14 have been shown, whereas in the structure illustrated in Figures 4 and 5, the filter element 14 has been omitted and corresponding changes made. In Figures 4 and 5, the ring 15 and the brackets 16 have been omitted and the upper edge of the filter element is positioned in the annular depression 3a. Since flange 8 is not needed, the lower edge of the wall 1 has been rolled as indicated at 59.

25 In other respects the structure illustrated in Figures 4 and 5 is substantially the same as that shown in Figures 1 and 2, and therefore no detailed description is considered to be necessary.

In Figures 1 and 2, member 40 has been shown as provided with small beads 60 and 61 located so as to be engaged by the edges of flanges 41 and 53, respectively, while in Figures 4 and 5 prick punch projections 62 are used for this purpose, and the object of beads 60 and 61 or projections 62 is to hold the diaphragms 45 and 52 in position during manufacture and thereafter.

40 In Figure 6 a slight modification has been shown in which the parts have been illustrated to an enlarged scale, and in which the cylindrical member 40 has been shown as provided with the bead 51 only. Diaphragm 52 is located underneath the bead 51, and is connected with the annular diaphragm 45 by angle strips 63 of the shape and character shown in section in Figure 7, 45 of which a plurality are employed. Strips 63 may be soldered or spot welded to the diaphragms. The bottom 42 is secured to member 40 by a crimped joint 41. When the construction illustrated in Figure 6 is used, the two diaphragms 45 and 52 can be inserted and removed as a unit.

50 In Figure 8 the diaphragm 52 has been shown as attached to member 40 by being spot welded thereto as indicated by numeral 64.

55 In Figure 9 the flange 24 has been shown as formed from a separate piece and attached to the tubular member by a crimped joint 65. Attention is called to the fact that the outer surfaces of the filter elements are upwardly and outwardly inclined so as to make it more difficult for dust to adhere and so as to facilitate the removal of any dust that does attach itself to these surfaces.

60 Particular attention is directed to the construction that makes it possible to remove the silencing element whenever this is not desired.

65 When the cleaner is used on trucks and tractors, it is evident that the silencing feature is of no importance, whereas the cleaning is of paramount importance, and in such cases, the silencer can be removed. On pleasure cars, which operate quietly, the silencer is desirable.

70 The silencer assembly has been so designed that the diaphragm 52 can first be put into position and the compartment thus formed filled with

silencing material, after which the cover plate 54 can be put into place and crimped by machinery. The annular compartment 49 can be constructed and inserted into the cylindrical member 40 and filled with silencing material after which the joint 5 41 can be crimped.

75 The cleaner is always installed so that the air can enter from below only so as to combine the separating action of gravity with that of the filter.

10 When the filter elements are assembled the very thin filter material is first soaked in a saturated solution of salt or sugar and then permitted to dry. When the water evaporates the salt or sugar residue crystallizes and makes the filter material compact and strong so that it can be handled with safety. After the filter element has been assembled it is washed in water which redissolves and removes the salt or sugar.

15 Many other materials besides those mentioned can be used, but salt is satisfactory and cheap.

20 In Figure 13 a slightly modified construction of the silencer assembly has been shown. The idea underlying this construction is to make the silencer of two complete units, one of which comprises a silencer like the one shown at the top in Figure 4, and the other an annular silencer unit like the one shown at the bottom in Figure 4. The diaphragm 52a differs from diaphragm 52 in this, that it is cup-shaped and has its circular wall 52b extending upwardly and joined to the cover 54 by a crimped joint 55. The lower silencer unit, which is annular, has the diaphragm 45a extending downwardly as indicated by 45b and connected to the base 42 by the crimped joint 41. 25 Walls 52b and 45b have each an external groove 67. A ring 40a of foraminated metal has two positioning beads 48a and 51a that serve as stops for the diaphragms 45a and 52a, and are also provided with smaller beads 66 that are so positioned 30 and shaped that they will engage the grooves 67. After the three parts have been completed the two silencer units are inserted in the ring 40a and pushed together until the beads 66 snap into 35 the grooves 67 and the assembly is complete.

40 The above silencer assembly can be somewhat more easily made than the one shown in Figure 4, but is the exact equivalent thereof in operation. The connection between the units and the ring 40a must be such that the parts will not come 45 apart under any strains to which they will normally be subjected.

45 The silencer assembly is an independent unit that can be removed and replaced at will, and can be reversed so that a manufacturer will be 50 in a position to sell a cleaner only (Figures 3 and 5) or a combined cleaner and silencer (Figures 1, 2 and 4), and to fit either an up or a down draft carburetor without carrying any additional stock.

55 The silencer assembly forms a sub-combination of this invention and is not an independent invention because it can be used only in the air cleaner shown and described.

60 Attention is called to the Venturi-shaped opening between the diaphragms 45 and 52 (Figures 1, 2 and 4), as this produces a difference in air pressure that gives a better distribution of the air and enhances the silencing effect.

65 What I claim and desire to secure by Letters Patent is

70 1. An air cleaner comprising a cup-like casing open at its lower end and provided with a top having a central aperture, an annular bottom positioned in the open end, an upwardly flaring filter element positioned between the top and the 75

- bottom, positioning means for engaging the top of the filter element, means on the bottom for engaging the lower edge of the filter element, a disk for closing the aperture in the top, a tubular outlet member communicating with the opening in the bottom, means extending between the disk and the bottom and comprising a bolt for applying a force to the edges of the filter element to hold the latter in place, means for securing the tubular member to the bottom, comprising an outwardly extending flange on the tubular member, of larger diameter than the opening in the bottom, and means for clamping the flange to the bottom.
- 15 2. An air cleaner and silencer comprising a cup-like casing open at its lower end, and provided with a top having a central aperture, a bottom located in the open end and provided with a central aperture, the top and the bottom having similarly shaped annular surfaces symmetrically arranged with respect to the center and in opposite relation, a connector assembly comprising a cylindrical foraminated member extending between the top and the bottom, an annular chamber formed by foraminated walls within the cylindrical member, at one end thereof, a cylindrical chamber at the other end of the cylindrical member, a cover for the last chamber, a bolt projecting through an opening in the center of the cover, a disk for covering the aperture in the top of the casing, said disk having a central opening through which the bolt extends, means for securing the bottom to the connector assembly comprising a plurality of angularly spaced bolts carried thereby for extending through correspondingly positioned holes in the bottom, a tubular member in communication with the interior of the silencer, and means for removably securing the tubular member at will to either the top or the bottom.
- 30 3. An air cleaner comprising in combination, a cup-like casing open at its lower end, and provided with a top, a removable bottom located in the lower end of the casing, the bottom and the casing having overlapping surfaces forming a substantially air tight connection, a ring of concavo-convex cross section spaced from the undersurface of the casing top, with its concave side facing downwardly, the bottom having two spaced concentric grooves on its upper surface, and a plurality of openings for the admission of air located between the grooves, two frusto-conical filter elements positioned between the bottom and the concavo-convex ring, one of the filter elements being smaller than the other and positioned with its larger end at the top, the larger element having its smaller end at the top, the tops of both filter elements being positioned in the groove in the concave surface of the ring, the lower ends of the filter elements being positioned in the grooves in the bottom, means for attaching the bottom to the top of the casing and a tubular member in communication with the interior of the cleaner.
- 45 4. An air filter comprising in combination, a cup-like casing having its open end directed downwardly and provided with an inwardly extending flange near its lower end, a frusto-conical filter element positioned in the casing with its larger end at the top, means carried by the top for engaging and positioning the upper end of the filter element, and a removable bottom, positioned with its edge overlapping the flange, the upper surface of the bottom having positioning means for engaging the lower end of the filter element, means for securing the bottom to the top of the casing, comprising a connector assembly located in the compartment formed by the top, the bottom and the filter, the connector assembly being independent of the filter and removably attached to both the top and the bottom.
- 50 5. An air cleaner comprising in combination, a cuplike casing positioned with its open end downwardly, the closed end having an opening, an inwardly extending flange at the open end of the casing, a circular bottom of greater diameter than the internal diameter of the flange, whereby it will overlap the latter, the bottom having a central opening, means for removably securing the bottom to the casing in sealing contact with the flange, means for closing one of the openings, means for connecting the other opening to a suction device, the bottom having a plurality of air inlet openings arranged in an annular row adjacent its periphery, an annular filter element of substantially inverted V-shaped cross section, positioned with its edges on opposite sides of the row of openings for separating the air inlet openings from the opening leading to the suction device, and means for securing the filter element to the bottom.
- 55 6. An air cleaner comprising in combination a cuplike casing positioned with its open end downwardly, the closed end having an opening, a circular bottom for closing the open end of the casing, means for effecting an air seal between the periphery of the bottom and the casing, the bottom having a central opening and two concentric grooves of different diameters in its upper surface, the space between the grooves being provided with air intake openings, means for removably securing the bottom in place, and an annular filter element of substantially inverted V-shaped cross section positioned with its edges in the grooves, means for holding the filter element in position, means for connecting one opening to a suction device and a cover for the other opening.
- 60 7. An air cleaner comprising in combination, a cup-like casing open at its lower end, and provided with a top, a removable bottom located in the lower end of the casing, the bottom and the casing having engaging surfaces forming a substantially air tight connection, a ring of concavo-convex cross section, positioned near the under surface of the top and spaced therefrom, with its concave side facing downwardly, the bottom having a concentric row of openings located adjacent its outer edge, two frusto-conical filter elements positioned between the bottom and the under surface of the concavo-convex ring, one of the filter elements being smaller than the other and positioned with its larger end at the top, the larger element having its smaller end at the top, the tops of both filter elements engaging the under surface of the ring, the lower ends of the filter elements engaging the bottom, on opposite sides of the openings, means for connecting the bottom and the ring, and means for connecting the bottom and the top.
